[57] CLAIM

The ornamental design for a handsaw frame, as shown
and described.

DESCRIPTION

FIG. 1 is a top perspective view of a handsaw frame
showing my new design;

FIG. 2 is a side elevational view thereof;

FIG. 3 is a left end elevational view thereof;

FIG. 4 is a right end elevational view thereof;

FIG. 5 is a top plan view thereof;

FIG. 6 is a bottom plan view thereof;

FIG. 7 is a top perspective view of a handsaw frame
showing an alternate embodiment of my new design;

FIG. 8 is a side elevational view thereof;

FIG. 9 is a left end elevational view thereof;

FIG. 10 is a right end elevational view thereof;

FIG. 11 is a top plan view thereof;

FIG. 12 is a bottom plan view thereof.

The broken line showing of the saw blade is for illustra-
tive purposes only and forms no part of the claimed
design.
